UNITED STATES PATENT OFFICE.

HUGH E. PLUNKETT, OF BOSTON, MASSACHUSETTS, ASSIGNOR TO JAMES BARRY, OF BOSTON, MASSACHUSETTS.

SWITCH-OPERATING DEVICE FOR LAMP-SOCKETS.

979,693.

Specification of Letters Patent. Patented Dec. 27, 1910.

Application filed April 9, 1910. Serial No. 554,555.

To all whom it may concern:

Be it known that I, HUGH E. PLUNKETT, a citizen of the United States, and resident of Boston, in the county of Suffolk and 5 State of Massachusetts, have invented new and useful Improvements in Switch-Operating Devices for Lamp-Sockets, of which the following is a specification.

This invention relates to switch operating devices for lamp sockets, and is particularly adapted to electric lamp sockets of the type commercially known as "pull sockets", in which the switch is operated for alternately turning the current on and off by 15 pulling a switch operating member, which is usually a chain or cord.

In the accompanying drawings, which illustrate one embodiment of the invention, Figure 1 is a side elevation, partly in section, 20 showing my attachment applied to an incandescent electric lamp socket; Fig. 2 is a plan view of said attachment.

Referring to the accompanying drawings, A represents an incandescent electric lamp socket of an ordinary and well known style, hung to extend downwardly as is customary, and holding a shade or globe C in the usual manner. Ordinarily the lamp socket is provided with a short sleeve a secured to 30 the side thereof about an aperture through which the switch operating member, or "chain-pull" a', extends, and from the mouth of which the chain depends. When the chain is pulled downward to operate the 35 switch, it rubs across the edge of the sleeve opening, and also across the edge of the shade or globe if the latter is of sufficient diameter to extend into the path of the chain, thus developing friction which makes 40 the chain pull hard, and also under some circumstances subjecting the shade or globe to danger of breaking.

The object of the present invention is to 45 provide a novel and improved device for operating the switch operating member which will avoid the aforesaid objections.

B represents a tubular arm, exteriorly screw threaded as shown at b, so that it may be screwed into the interiorly screw threaded sleeve a. The upper side of the tubular arm B is cut away on top at its outer end, and the remaining lower part is bent downward to form an integral downwardly bent bracket portion b'. The sides of said 50 bracket portions are folded toward each

other to form the ears b² between which is pivoted the lower end of a lever D. The lever D is preferably formed as shown in the drawings, with the lower portion between the pivot b² and the point of attachment d to the switch-operating member a', standing substantially upright, and the upper part of the lever laterally turned outward to form an outwardly extending operating portion, to the end of which an operating cord E is attached. By reason of the relative arrangement of the point of attachment d and the pivot b', one approximately over the other, it will be seen that the switch-operating member a' will be in a line 60 nearly tangent to the arc of the circle described by said point of attachment and will therefore be pulled by the lever substantially straight outward without material deflection from its normal line. Secured to 65 the lever D at a point opposite the opening of the tube B is a holder to which is attached the switch operating member a'. In the form herein shown wherein the switch operating member consists of a chain such as is 70 usually employed, the holder consists of a loop or bracket d provided with a notch d' in its upper edge to engage and hold one of the links or balls of the chain a'. The chain of an ordinary fixture may thus be used by 75 simply passing it through the tube B, severing it at the required point, and lodging the end link or ball in the notched holder d as shown in the drawings.

To operate the device the cord E is pulled 80 downward, which swings the lever D to the position shown in dotted lines in Fig. 1 and pulls the chain a' outward, thus operating the switch controlled thereby. It is not 85 necessary to show details of the switch which forms no part of the present invention and may be of any well known and approved form, which is operated by pulling a switch operating member.

When the device is in its normal, retracted position, the tubular arm B constitutes a protective casing for the switch operating chain a' preventing the accumulation thereon of dust and dirt, and the tubular form 90 of the arm renders it very stiff and strong.

I claim:

1. In combination with a lamp socket having a switch operating member, an arm secured to and extending laterally from said 100 socket, and a lever fulcrumed at its lower 105

110 portion of the arm, the lever having a portion pivoted to the arm and a portion extending laterally from the pivot.

end to the outer end of said arm and attached at its middle part to said switch operating member, adapted when swung on its fulcrum to pull said switch operating member, the upper end of said lever being turned laterally outward to form an outwardly extending operating portion, and said lever standing substantially upright between the pivot and the point of attachment to the switch - operating member, whereby the switch - operating member will be pulled substantially straight outward by the lever without material deflection.

2: In combination with a lamp socket having a switch operating member, a tubular arm secured to and extending laterally from said socket through which said switch operating member passes, and a lever to which said switch operating member is attached, pivoted at the outer end of said tubular arm and adapted when swung on its pivot to pull said switch operating member.

3. In combination with a lamp socket having an aperture through its side, a sleeve secured to the socket about said aperture, a tubular arm separably attached to said sleeve, a switch operating member passing through said sleeve and tubular arm, and a lever to which said switch operating member is attached, pivoted at the outer end of said tubular arm, adapted when swung on its pivot to pull said switch operating member.

4. In combination with a lamp socket having an aperture through its side, a screw threaded sleeve secured to the socket about said aperture, a screw threaded tubular arm separably attached to said sleeve, a switch operating member passing through

said sleeve and tubular arm, and a lever to which said switch operating lever is attached, pivoted at the outer end of said tubular arm, adapted when swung on its pivot to pull said switch operating member.

5. In combination with a lamp socket having a switch operating member, a tubular arm secured to and extending laterally from said socket through which said switch operating member passes, a downwardly extending bracket at the end of said tubular arm, and a lever pivoted at its lower end to said bracket, and attached to said switch operating member at a point substantially opposite the end of the tubular arm.

6. As a new article of manufacture, an attachment for lamp sockets, comprising a tubular arm, formed with an integral downwardly bent bracket portion; a lever pivoted at its lower end to said bracket portion, and provided with means to engage a cord or chain opposite the opening of the tubular arm, and a flexible lever-operating member attached to the upper end of said lever.

7. As a new article of manufacture, an attachment for lamp sockets, comprising a tubular arm, formed with an integral downwardly bent bracket portion, a lever pivoted at its lower end to said bracket portion, and provided with a notched chain holder opposite the opening of the tubular arm, and a flexible lever operating member attached to the upper end of said lever.

Signed by me at Boston, Massachusetts this sixth day of April 1910.

HUGH E. PLUNKETT.
